UNITED STATES PATENT OFFICE

2,137,437

DETENTION WINDOW

William D. Bayley, Springfield, Ohio, assignor to
The William Bayley Company, Springfield,
Ohio, a corporation of Ohio

Application March 28, 1935, Serial No. 13,456

25 Claims. (Cl. 189—64)

This invention relates to detention windows and more particularly to the closure assembly associated with the ventilating area.

Extending muntin bars across the ventilating areas so as to function as detention bars is shown to be old in the Bayley Patents Nos. 1,948,159 and 1,948,160, but in each of these the closure for the ventilating area has been mounted in a plane offset to one side only with respect to the 5 detention bars. In the present embodiment the 10 detention bars integral with or suitably united to the muntin bars have been arranged to prevent the escape of inmates through the ventilating area and the closure centrally pivoted so as to 15 swing both inwardly and outwardly. This has been accomplished by mounting the detention bars on the inside of the outwardly swinging portion of the closure and on the outside of the inwardly 20 swinging portion thereof.

20 An object of the invention is to provide a detention window with detention bars for preventing the escape through the ventilating area on either side of a centrally pivoted closure.

Another object of this invention is to provide 25 screens for screening the ventilating area, the screen being located on the same side as the detention bars on both sides of the closure.

Another object of this invention is to provide 30 a detention assembly that is cheap, efficient and dependable.

Another object of this invention is to provide a pivotally mounted closure which may be substantially flush with the window assembly when in closed position, the detention bars also may 35 be substantially flush with the outside of the window assembly.

Another object of this invention is to provide 40 a new and novel pivotal muntin bar.

With the above primary and other incidental 45 objects in view, as will more fully appear in the specification, the invention consists of the features of construction, the parts and combinations thereof, and the mode of operation, or their equivalents, as hereinafter described and set forth in the claims.

In the drawings, Fig. 1 shows a perspective view 50 of a detention window assembly as seen from the outside. Fig. 2 is a sectional view taken across the ventilating area with the ventilating closure in closed position taken below the pivot of the closure. Fig. 3 is a similar view to that of Fig. 2 but is taken above the pivot of the closure. Fig. 4 is a vertical sectional view of Fig. 1 taken 55 through the closure when in closed position. Fig. 5 is a fragmentary sectional view of the trans-

verse pivotal bar of the closure as seen when the closure is partially open. Fig. 6 shows another modification of the pivotal bar of a closure. Fig. 7 is another modification showing the screen slipped in a well provided therefor by the detention bars. Figs. 8 and 9 disclose modifications. Fig. 10 is an exploded view of the pivotal assembly.

Fig. 11 discloses a fragmentary sectional view taken horizontally across a ventilating area of 10 another modification. Fig. 12 is a fragmentary sectional view similar to that shown in Fig. 11 with the closure shown in open position. Fig. 12 shows a modification slightly different from Fig. 11. Fig. 13 is a fragmentary sectional view of a 15 portion of a closure showing another modification.

Like parts are indicated by similar characters of reference throughout the several views.

In my former patents referred to above, the centrally pivoted closure could not be used with 20 the detention bars for the reason that the detention bars are all located on one side of the closure which would prevent the closure from swinging in opposite directions about a pivot. In the present embodiment the ventilating closure 25 which swings both outwardly and inwardly abuts the detention bars located on the inside of the outwardly swinging portion of the closure and abuts the detention bars on the inside of the outwardly swinging portion, the detention bars over 30 the lower portion of the window being located on one side of the closure and the bars over the upper portion on the opposite side thereof. In addition to the detention bars, screens cover the lower portion and the upper portion, these 35 screens being oppositely disposed. The closure when in closed position is arranged to be substantially co-planar with the window, the glazing of the stationary portion of the window and the glazing of the closure being substantially in 40 the same plane.

Referring to the drawings, a plurality of transversely arranged muntin bars 10 and 12, vertically and horizontally disposed, divide the window into a plurality of spaces, some of which 45 are glazed spaces 14 leaving a group of unglazed spaces 16 which form a ventilating area. Vertical bars 18 arranged in aligned relation with respect to the muntin bars 10 extend across the upper half and across the lower half of the ventilating areas but on opposite sides of the closure 20 pivotally mounted at 22. In addition to the vertical bars, horizontal bars 24 extend across the ventilating area both above and below the closure in aligned relation with the horizontal 50 55

muntin bars 12. The transverse bars 18 and 24 may be integral with the bars 10 and 12 respectively, or attached thereto by welding or in any suitable manner.

- 5 These transversely arranged muntin and detention bars cooperate to prevent the escape of human bodies through the window assembly. Such structures may be used in penal institutions, asylums, and for that matter hospitals, hotels, 10 apartments and homes where protection from either intentional or accidental escape or unauthorized entry through the window is desirable. The bars 18 and 24 located above the pivotal bar 28 and on the outside of the upper portion of 15 the closure swinging inwardly prevents the escape through this portion of the ventilating area when the closure is open. Likewise the transverse bars 18 and 24 located below the pivotal bar 28 and inside the lower and outwardly swinging portion 20 prevents escape through this portion.

As may best be seen by referring to Figs. 2, 3 and 4, the glazing of the closure 20 is co-planar with the glazing of the glazed spaces 14. A pair of bars 26 and 27, shown in Fig. 4, extend across 25 the terminals of the vertical detention bars 18 and are arranged to slidably engage the pivotal bar 28 of the closure 20.

The closure frame which includes the vertical bars 34 and horizontal bars 36 is supported upon 30 the pivotal bar 28. The closure 20 may also be provided with the transversely arranged muntin bars 38 and 40 extending from frame bar 36 to the pivotal bar 28 and between the frame bars 34 respectively. Although for the purposes of illustration only one horizontal bar 40 has been shown in each half of the window, a greater or lesser number of such bars may be used. The bars 38 and 40 have been shown in aligned relation with respect to the detention bars 18 and 24 respectively so as to hide the same when in closed position and to have the appearance of continuations of the bars 10 and 12. The closure may have a single pane on each side of the arcuate or pivotal bar 28.

45 A pair of screen frames 44, one located on the inside and above the pivot of the closure as viewed in Fig. 1, and the other on the outside and below the pivot of the closure, are shown. The screen frame is preferably held in position by metallic clips 46 which permits the insertion of the screen from one side of the closure. If the operator is on the inside of the detention window inserting the screen it will of course be necessary to raise the screens from the outside within reach of the operator who may then slip the screen in position. The clips 46 are preferably resilient so as to permit flexing while inserting the screen and tightly hold the screen in position.

The pivotal bar 28 is substantially S-shaped 60 but is provided with a dependent flange to complete the arcuate surface 30. The opposite side 32 of the bar is also arcuate and substantially concentric with respect to the arcuate surface 30. The ends of the pivotal bar 28 are pivotally 65 mounted in the muntins bounding the ventilating area. The center of the arcuate surfaces 30 and 32 is aligned with the axis of the pivots. The glass 50 is held in position with putty 60 seated in suitable recesses provided therefor in the 70 pivotal bar 28. As the window is swung from a closed position to an open position the arcuate surfaces 32 continue contacting the transverse bars 26 and 27 so as to prevent insects and the like from entering the closure.

75 In the modifications shown in Figs. 1, 4, 5 and 6

the closures are pivoted on the horizontal pivot. Instead of a horizontal pivot a vertical pivot could be used. In either case the closure greatly deters the escape or unauthorized entry through the closure, virtually functioning as a detention bar 5 both in open and closed positions. The pivotally mounted bar 28 is especially effective to deter the escape through the window opening.

In Figs. 8 and 9 the flanges of the bars 80 and 82, the former of which may be a pivotal bar, 10 are covered or shielded by metallic shields 83, 84 and 86. These metallic shields may be made of copper or other non-corroding metal so as to permit the use of ferrous materials in the bars 80 and 82 to reduce corrosion thereof. If the pivotal 15 bar is not lined or covered as disclosed in Fig. 8, the pivotal bar 28 as disclosed in Figs. 1, 4 and 5, and the bar 62 as disclosed in Fig. 6, are preferably made from aluminum, brass or other rust resisting metals. The friction extending between 20 the surfaces 30 and 32 and the detention bars 26 and 27 respectively, may be utilized to hold the window closure in any adjusted position. When either the bar 28 is made of aluminum or brass or the detention bars 26 and 27 made of 25 this material, the friction between the surfaces 30 and 32 with the detention bars 26 and 27 respectively may be more advantageously utilized to effect and hold the window closure in adjusted position.

30 Referring to Fig. 10 an exploded view of one type of pivotal mounting for the closure has been shown. The muntin bar 10 bounding the ventilating area carries a tubular member 90 suitably attached to the web of the muntin bar, as by welding. Mounted within this tubular member 90 is a rotatable sleeve 92, provided with a pair of diametrically arranged kerfs or slots 94 in which is seated the web of the pivotally mounted muntin bar 28, only a fragment of which has 40 been shown for the purpose of illustration. Member 92 rotates freely within the tubular sleeve 90 and provides a cheap and efficient pivotal assembly.

The screen and detention bars may be formed 45 into a unitary structure, that is, the screen may be fixedly attached to the detention bars.

In Fig. 6 a substantially C-shaped pivotal muntin bar 62 has been shown instead of the pivotal bar 28 as disclosed in Figs. 4 and 5. 50 This pivotal bar 62 is provided with a longitudinal recess 64 which supports the glazing 50. The projections on the interior caused by the longitudinal recess forms a seat 66 for supporting the lower glass pane. The arcuate surfaces 68 55 and 70 are concentric with respect to the pivot of the bar 62 and slidably engage the screen frames or the detention bars. The detention bars 26 and 27 may be spaced away from the arcuate surfaces 30 and 32 or 68 and 70 as the case may 60 be, as has the detention bar 69 shown in Fig. 6. If the detention bars do not contact the arcuate surfaces of the pivot bar of the closure, then it is quite desirable that the screen frame do so, as shown at 71 in Fig. 6. The detention bar 69 may 65 be spaced several inches from the pivotal bar, probably four or five inches therefrom, or more. Obviously the space between 29 and the pivotal bar 62 must be sufficiently small to prevent the passage of a human body therethrough.

70 In the modification disclosed in Fig. 7, transverse detention bars 72 and 74 extend across the ventilating area, the detention bars 72 and 74 being preferably aligned with the muntin bars in the closure. The detention bars 72 and 74 are 75

offset so as to provide a well 76 into which the screen 78 may be inserted. Thus the screen is found intermediate the offset detention bars 72 and 74 and the closure. The screen may be mounted upon a suitable frame, preferably flexible, which in thickness is not much greater than the screen per se.

In Fig. 11 a modification has been shown wherein both screens are inserted from the inside of the window. The screen over the outwardly swinging portion of the window is located on the inside of the window, the screen over the remainder is located outside of the closure. This has been accomplished by arranging the detention bars 102, welded to the angle bar 105, in offset relation with respect to the plane of the window, so as to provide a pocket 104 for the reception of the screen 100. The upper end of the detention bar is preferably welded directly to the muntin bar bounding the ventilating area. The screen may be removed by forcing the lower portion of the frame inwardly to permit the upper portion to clear the flange 103. The screen 110 extending over the lower portion of the closure, that is, the outwardly swinging portion, is also inserted from the inside. It may be removed in a manner similar to that disclosed in Fig. 2. The screen may be held in position by suitable clips not shown. The detention bars 112 are located intermediate the screen 110 and the closure.

In Fig. 12 screens 100 and 110 have been inserted from the outside. In Fig. 13 instead of the detention bars being offset in their entirety, detention bar 114 has been provided with an offset portion for receiving the screen frame 100. The screen in this modification extends parallel and in proximity to the detention bars 114 over a greater portion of the closure.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. A detention window assembly including a plurality of transversely arranged muntin bars dividing the window into a plurality of spaces, some of which are glazed leaving a space vacant for ventilating area, a closure for the ventilating area pivotally mounted for swinging movement into opposite directions, whereby the portion of the closure located on one side of the pivot swings inwardly and the other portion located on the other side of the pivot swings outwardly, externally mounted detention bars placed over the portion of the area closed by the inwardly swinging portion of the closure, internally mounted detention bars located over the remainder of the ventilating area, and a pair of screens

insertable from the same side, one of which is located intermediate the detention bars and the closure and the other extending over the remaining portion of the ventilating area, whereby the corresponding detention bars extend between the closure and said other screen.

2. A detention window assembly including a plurality of transversely arranged muntin bars dividing the window into a plurality of spaces, some of which are glazed, leaving a group of spaces vacant for ventilating area, a closure for the ventilating area mounted upon a pivotally mounted horizontal bar having arcuate surfaces, said closure having swinging movement into opposite directions whereby the portion of the closure located above the bar swings in one direction and the portion located below the bar swings in the opposite direction, internally mounted detention bars contacting the arcuate surface of the pivotal bar overlying the portion of the ventilating area closed by the outwardly swinging portion of the closure, and externally mounted detention bars overlying the inwardly swinging portion of the closure.

3. A detention window assembly including a plurality of transversely arranged muntin bars dividing the window into a plurality of spaces, some of which are glazed, leaving a group of spaces vacant for ventilating area, a closure for the ventilating area pivotally mounted for swinging movement into opposite directions whereby the portion located on one side of the pivot swings inwardly and the other portion located on the other side of the pivot swings outwardly, externally mounted detention bars placed over the portion of the ventilating area closed by the inwardly swinging portion of the closure and internally mounted detention bars located over the remaining portion of the ventilating area, said bars being arranged in aligned relation with the muntin bars of the window so as to simulate uninterrupted detention bars.

4. A detention window assembly including a plurality of transversely arranged muntin bars dividing the window into a plurality of spaces, some of which are glazed, leaving a group of spaces vacant for ventilating area, a closure for the ventilating area pivotally mounted for swinging movement into opposite directions said closure having transversely arranged muntin bars and externally mounted detention bars placed over the portion of the ventilating area closed by the inwardly swinging portion of the closure and internally mounted detention bars mounted over the remaining portion of the ventilating area, the muntin bars of the closure and the detention bars being arranged in aligned relation whereby one set of bars is concealed by another.

5. A detention window assembly including a plurality of transversely arranged muntin bars dividing the window into a plurality of spaces, some of which are glazed, leaving a group of spaces vacant for ventilating area, a closure for the ventilating area pivotally mounted for swinging movement into opposite directions whereby the portion located on one side of the pivot swings inwardly and the portion located on the other side of the pivot swings outwardly, externally mounted detention bars overlying the area closed by the inwardly swinging portion of the closure, internally mounted detention bars located over the remaining portion of the ventilating area, and screens contiguous to the detention bars for screening the ventilating area.

6. A detention window assembly including a

plurality of transversely arranged muntin bars dividing the window into a plurality of spaces, some of which are glazed, leaving a group of spaces vacant for ventilating area, a closure for the ventilating area pivotally mounted for swinging movement into opposite directions whereby the portion located on one side of the pivot swings inwardly and the portion located on the other side of the pivot swings outwardly, externally mounted detention bars overlying the area closed by the inwardly swinging portion of the closure, internally mounted detention bars located over the remaining portion of the ventilating area, a removably mounted screen assembly mounted contiguous to the internally mounted detention bars and a second screen assembly mounted contiguous to the externally mounted detention bars.

7. A closure assembly for a ventilating area including a frame, a closure pivotally mounted for swinging movement in opposite directions whereby one portion swings inwardly and another portion swings outwardly, protective means carried by said frame and overlying the outwardly swinging portion of the closure, an externally protective means overlying the inwardly portion of the closure, said closure including a hollow substantially C-shaped pivotal bar having its axis symmetrical with the closure arcuate surfaces contacting said protective means, the center of the radius of curvature of said arcuate surfaces being located between the planes formed by the margins of the frame, said C-shaped bar being adapted to support glazing of the closure, the glazing extending in one direction being seated within the hollow of the C-shaped bar and the glazing extending in the opposite direction being seated on outer surface of the C-shaped bar.

8. A closure assembly for a ventilating area including a frame, a closure pivotally mounted for swinging movement in opposite directions whereby one portion swings inwardly and another portion swings outwardly, protective means carried by said frame and overlying the outwardly swinging portion of the closure, oppositely disposed protective means overlying the inwardly swinging portion of the closure, said closure including a C-shaped pivotal bar the axis of which is within the confines of the closure and located between the planes formed by the outer margins of the frame, said C-shaped pivotal bar having arcuate surfaces contacting the protective means and including a longitudinal recess in which is seated the glazing of the closure.

9. A closure assembly for a ventilating area including a frame, a closure pivotally mounted for swinging movement in opposite directions whereby one portion swings inwardly and another portion swings outwardly, protective means carried by said frame and overlying the outwardly swinging portion of the closure, oppositely disposed protective means overlying the inwardly swinging portion of the closure, said closure including a substantially tubular bar the periphery of which contacts said protective means, said tubular bar being symmetrical with the pivotal axis of the closure and having a longitudinal groove intermediate the oppositely disposed protective means for supporting the glazing of the closure, the center of the radius of curvature of the tubular bar being located between the planes formed by the margins of the frame.

10. A detention window assembly including a plurality of transversely arranged muntin bars dividing the window into a plurality of spaces, some of which are glazed, leaving a group of

spaces vacant for ventilating area, a closure for the ventilating area pivotally mounted for swinging movement into opposite directions whereby the portion located on one side of the pivot swings inwardly and the remainder swings outwardly, externally mounted detention bars placed over the portion of the ventilating area closed by the inwardly swinging portion of the closure, internally mounted detention bars located over the remaining portion of the ventilating area, and a screen assembly including a screen associated with the external bars for protecting the portion of the ventilating area closed by the inwardly swinging portion and a screen associated with the internally mounted detention bars for protecting the remainder of the ventilating area.

11. A detention window assembly including a plurality of transversely arranged muntin bars dividing the window into a plurality of spaces some of which are glazed leaving a group of spaces vacant for ventilating area, a movably mounted closure for the ventilating area, externally mounted detention bars placed over a portion of the ventilating area and internally mounted detention bars extending over the remaining portion of the ventilating area, said closure positioned intermediate the detention bars.

12. A detention window assembly including a plurality of muntin bars dividing the window into a plurality of spaces, some of which are glazed leaving a group of spaces vacant for ventilating area, a closure unit for the ventilating area including a fixed frame and a closure movably mounted therein, detention bars overlying at least a portion of the ventilating area to prevent the free egress and ingress of human bodies therethrough, the detention bars being deflected to form a pocket, and a screen for covering the ventilating area, said screen being positioned in the pocket.

13. A detention window assembly including a plurality of transversely arranged muntin bars dividing the window into a plurality of spaces, some of which are glazed leaving a group of spaces vacant for ventilating area, detention bars having at least a portion thereof deflected out of the plane of the window, said detention bars extending over the ventilating area to prevent the ingress and egress of human bodies from the more vulnerable area, a closure unit for the ventilating area, the closure unit including a fixed frame and a movable closure mounted therein arranged to form a pocket intermediate the detention bars and the closure unit and a screen mounted in said pocket for protecting at least a portion of the ventilating area.

14. A detention window assembly including a plurality of transversely arranged muntin bars dividing the window into a plurality of spaces, some of which are glazed, leaving a group of spaces vacant for ventilating area, a closure for the ventilating area mounted upon a pivotally mounted horizontal bar having arcuate surfaces of rust resisting metal, the center of the radius of curvature of said arcuate surfaces located between the planes common to the margins of the muntin bars, said closure having swinging movement into opposite directions whereby the portion of the closure located above the bar swings in one direction and the portion located below the bar swings in the opposite direction, internally mounted detention bars contacting the arcuate surface of the pivotal bar overlying the portion of the ventilating area closed by the outwardly swinging portion of the closure, and externally

mounted detention bars overlying the inwardly swinging portion of the closure.

15. A detention window assembly including a plurality of transversely arranged muntin bars dividing the window into a plurality of spaces some of which are glazed leaving a group of spaces vacant for ventilating area, a pivotally mounted closure for the ventilating area, said closure having a central pivotal bar provided with 10 arcuate surfaces having the center of radius of curvature located between the planes common to the margins of the muntin bars, said closure being mounted upon a pair of tubular hinge members telescopically engaging a second pair of tubular hinge members fixedly attached to the muntin bars bounding the ventilating area, the axis of the tubular member being coincident with said center of radius of curvature, externally mounted 15 detention bars placed over a portion of the ventilating area, and internally mounted detention bars extending over the remaining portion of the ventilating area, said closure being positioned intermediate the detention bars but in engagement therewith.
20. A detention window assembly including a plurality of transversely arranged muntin bars dividing the window into a plurality of spaces some of which are glazed leaving a group of spaces vacant for ventilating area, a pivotally mounted closure for the ventilating area, said closure having an arcuate bar concentrically disposed with respect to the axis of the pivotal mounting, externally mounted detention bars placed over a portion of the ventilating area, internally mounted detention bars extending over the remaining portions of the ventilating area, said closure positioned intermediate the detention bars, a screen mounted over the portion of the ventilating area protected by the externally mounted detention bars and a second screen mounted over the area protected by the internally mounted detention bars, said screens cooperating with said arcuate bar to form fly tightness.
25. A detention window assembly including a plurality of transversely arranged muntin bars dividing the window into a plurality of spaces some of which are glazed leaving a group of spaces vacant for ventilating area, a pivotally mounted closure for the ventilating area, said closure including an arcuate bar concentrically mounted with respect to the pivot of the closure, said concentric bar having longitudinal grooves for the reception of the glazing, externally mounted 30 detention bars placed over a portion of the ventilating area, and internally mounted detention bars extending over the remaining portion of the ventilating area, said closure being positioned intermediate the detention bars.
35. A detention window assembly including a plurality of transversely arranged muntin bars dividing the window into a plurality of spaces some of which are glazed leaving a group of spaces vacant for ventilating area, a pivotally mounted closure for the ventilating area, said closure including a bar having non-ferrous metallic arcuate surfaces concentrically disposed with respect to the pivot of the closure, which pivot is located between the planes formed by the margins of the muntin bars, externally mounted 40 detention bars placed over a portion of ventilating area, and internally mounted detention bars extending over the remaining portion of the ventilating area, said closure being positioned intermediate the detention bars.
45. A detention window assembly including a plurality of transversely arranged muntin bars dividing the window into a plurality of spaces some of which are glazed leaving a group of spaces vacant for ventilating area, a pivotally mounted closure for the ventilating area, said closure including a bar having non-ferrous metallic arcuate surfaces concentrically disposed with respect to the pivot of the closure, which pivot is located between the planes formed by the margins of the muntin bars, externally mounted 45 detention bars placed over a portion of ventilating area, and internally mounted detention bars extending over the remaining portion of the ventilating area, said closure being positioned intermediate the detention bars.
50. A detention window assembly including a plurality of transversely arranged muntin bars dividing the window into a plurality of spaces some of which are glazed leaving a group of spaces vacant for ventilating area, a pivotally mounted closure for the ventilating area, said closure including a bar having non-ferrous metallic arcuate surfaces concentrically disposed with respect to the pivot of the closure, which pivot is located between the planes formed by the margins of the muntin bars, externally mounted 50 detention bars placed over a portion of ventilating area, and internally mounted detention bars extending over the remaining portion of the ventilating area, said closure being positioned intermediate the detention bars.
55. A detention window assembly including a plurality of transversely arranged muntin bars dividing the window into a plurality of spaces some of which are glazed leaving a group of spaces vacant for ventilating area, a pivotally mounted closure for the ventilating area, said closure including a bar having non-ferrous metallic arcuate surfaces concentrically disposed with respect to the pivot of the closure, which pivot is located between the planes formed by the margins of the muntin bars, externally mounted 55 detention bars placed over a portion of ventilating area, and internally mounted detention bars extending over the remaining portion of the ventilating area, said closure being positioned intermediate the detention bars.
60. A detention window assembly including a plurality of transversely arranged muntin bars dividing the window into a plurality of spaces some of which are glazed leaving a group of spaces vacant for ventilating area, a pivotally mounted closure for the ventilating area, said closure including a bar having non-ferrous metallic arcuate surfaces concentrically disposed with respect to the pivot of the closure, which pivot is located between the planes formed by the margins of the muntin bars, externally mounted 60 detention bars placed over a portion of ventilating area, and internally mounted detention bars extending over the remaining portion of the ventilating area, said closure being positioned intermediate the detention bars.
65. A detention window assembly including a plurality of transversely arranged muntin bars dividing the window into a plurality of spaces some of which are glazed leaving a group of spaces vacant for ventilating area, a pivotally mounted closure for the ventilating area, said closure including a bar having non-ferrous metallic arcuate surfaces concentrically disposed with respect to the pivot of the closure, which pivot is located between the planes formed by the margins of the muntin bars, externally mounted 65 detention bars placed over a portion of ventilating area, and internally mounted detention bars located over the remaining portion of the ventilating area.
70. A detention window assembly including a plurality of transversely arranged muntin bars dividing the window into a plurality of spaces some of which are glazed leaving a group of spaces vacant for ventilating area, a pivotally mounted closure for the ventilating area, said closure including a pivot bar having a non-corrosive surface, externally mounted 70 detention bars placed over a portion of the ventilating area, and internally mounted detention bars located over the remaining portion of the ventilating area.
75. A detention window assembly including a plurality of transversely arranged muntin bars dividing the window into a plurality of spaces some of which are glazed leaving a group of spaces vacant for ventilating area, a pivotally mounted closure for the ventilating area, said closure including a pivot bar having a non-corrosive surface, externally mounted 75 detention bars placed over a portion of the ventilating area, and internally mounted detention bars located over the remaining portion of the ventilating area.

19. A detention window assembly including a plurality of muntin bars dividing the window into a plurality of spaces some of which are glazed leaving a group of spaces vacant for ventilating area, a closure unit for the ventilating area including a closure movably mounted therein, detention bars overlying at least a portion of the ventilating area to prevent the free egress and ingress of human bodies therethrough, the detention bars being deflected to form arcuate portions constituting a pocket and a screen for covering the ventilating area, said screen being positioned in the pocket.

20. A detention window assembly including a plurality of transversely arranged muntin bars dividing the window into a plurality of spaces some of which are glazed leaving a group of spaces vacant for ventilating area, a pivotally mounted closure for the ventilating area, said closure including a bar having non-ferrous metallic arcuate surfaces of rust-resisting material, externally mounted 15 detention bars placed over a portion of the ventilating area arranged in scraping relation with respect to the arcuate surfaces and internally mounted detention bars extending over 20 the remaining portion of the ventilating area and arranged in scraping relation with respect to other portions of the arcuate surfaces, said closure being positioned intermediate the detention bars.

21. A detention window assembly including a plurality of transversely arranged muntin bars dividing the window into a plurality of spaces, some of which are glazed, leaving a group of spaces vacant for ventilating area, a closure for 30 the ventilating area pivotally mounted upon a horizontal bar constituting an axis for swinging movement in opposite directions, whereby the portion of the closure located below the axis swings in one direction and the portion located above the axis in the opposite direction, at least one bar thereof having a surface covered with non-corrosive metal, externally mounted 35 detention bars placed over the portion of the closure swinging inwardly, and internally mounted 40 detention bars extending over the outwardly swinging portion.

22. A detention window assembly including a plurality of transversely arranged muntin bars dividing the window into a plurality of spaces, some of which are glazed, leaving a group of spaces vacant for ventilating area, a closure for 45 the ventilating area pivotally mounted for swinging movement into opposite directions, whereby the portion located on one side of the pivot swings outwardly and the remainder of the closure swings inwardly, a window pane mounted in the outwardly swinging portion of the closure, another window pane mounted in the inwardly swinging portion of the closure below the pivot, 50 said pivot including a pair of telescopically mounted tubular members, externally mounted detention bars placed over the portion of the ventilating area protected by the inwardly swinging portion of the closure, and internally mounted 55 detention bars located over the remaining portion of the ventilating area.

23. A detention window assembly including a plurality of transversely arranged muntin bars dividing the window into a plurality of spaces some of which are glazed leaving a group of spaces vacant for ventilating area, a movably mounted closure for the ventilating area including a pivot bar having a non-corrosive surface, externally mounted 60 detention bars placed over a portion of the ventilating area, and internally mounted detention bars located over the remaining portion of the ventilating area.

half of the ventilating area on the outside of the closure, internally mounted detention bars extending over the balance of the ventilating area, said internally mounted bars extending inside 5 the closure, and a pair of screens, one edge of each screen cooperating with said non-corrosive surface to provide fly-tightness.

24. In a detention window assembly a frame, a closure having a central bar provided with an 10 arcuate outer surface, means for pivotally mounting said closure in said frame for swinging movement in opposite directions, whereby the portion of the closure located on one side of the pivot swings inwardly and the remainder swings outwardly, said means including telescoping hinge members, the outer diameter of the larger member being less than the diameter of the arcuate surface of said central bar, externally mounted 15 detention bars carried by said frame and placed over the portion closed by the inwardly swinging portion of the closure, and internally mounted

detention bars located over the remaining portion of the closure to prevent the escape of human beings through said frame.

25. A closure assembly for a ventilating area having a frame, a closure pivotally mounted for 5 swinging movement in opposite directions, whereby one portion swings inwardly and another portion swings outwardly, said closure including a hollow substantially C-shaped pivotal bar having its axis symmetrical with the closure, the center of the radius of curvature of the arcuate surface of the C-shaped bar being located between the planes formed by the margins of the frame, said C-shaped bar being adapted to support the glazing of the closure, the glazing extending in one direction being seated within the hollow of the C-shaped bar and the glazing extending in the opposite direction being seated on the outer surface of the C-shaped bar. 10 15
